CLAIM

The ornamental design for an electronic display unit, as shown and described.

DESCRIPTION

FIG. 1 is a front perspective view of the electronic display unit;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and,

FIG. 7 is a bottom view thereof.

The broken lines on the front and back of the display show environment that forms no part of the claimed design. All other broken lines show portions of the electronic display unit that form no part of the claimed design.

1 Claim, 5 Drawing Sheets
